UNITED STATES PATENT OFFICE.

WILLIAM C. CRIST, OF BLUE ISLAND, ILLINOIS.

SMOKE DEFLECTOR.

Application filed March 5, 1927. Serial No. 173,150.

My invention relates to a smoke deflector and has particular reference to a smoke deflector for application to a railway locomotive by means of which the air is deflected above the stack causing the smoke to rise above the locomotive and out of the view of the enginemen, and also above the train without entering the coaches and causing discomfort to the passengers and also prevents the gas from oil burning locomotives from entering the coaches.

Another and further object of my invention is the provision of a smoke deflector having a hinged section at the top thereof, which is adapted to rise at a predetermined speed of the train and to drop down when the speed of the train is less than a predetermined rate of travel, thereby allowing the locomotive to pass under smoke jacks and the like without damaging the smoke deflector.

Another and further object of my invention is the provision of a smoke deflector which is adapted to cause the air to travel upward over the smoke stack when the locomotive is in forward motion at a predetermined rate of speed, thereby reducing the resistance of the air to the ejection of the smoke from the stack and also reducing the back pressure on the exhaust nozzles, thereby increasing the draft and allowing for more free operation of the locomotive.

These and other objects of my invention will be more fully and better understood by reference to the accompanying sheet of drawings and in which:

Figure 1 is a diagrammatic view in front elevation of a locomotive, showing my invention attached thereto;

Figure 2 is a side view of the device shown in Figure 1; and

Figure 3 is a detailed sectional view of the upper end of a smoke stack with the deflector positioned in front of the said stack.

Referring now specifically to the drawings and in which like reference characters refer to like parts throughout, a locomotive having the usual smoke box construction 10 at the front end thereof, is shown, to which the usual smoke stack 11 is applied in the usual manner. The smoke deflector comprises a member having a vertical back sheet 12 curved at its lower edge 13 to conform to the contour of the smoke box of the locomotive, and has a pair of wings 14 and 15 at the sides thereof, these wings having out-

wardly bent portions 16 and 17 at the lower edges thereof through which rivets 18 pass by means of which the device is secured to the upper side of the smoke box immediately in front of the smoke stack. The wings 14 and 15 are somewhat triangular in shape, being wider at their bottom portions than at the top, and are formed preferably integrally with the back member 12, thereby forming a channel within which the air is received as the locomotive is traveling. At the upper end of the member 12 is secured a second member comprising a back wall portion 19 and a pair of wing portions 20 and 21 on each side thereof, these wing portions extending outside of and overlapping the wing portions 14 and 15 formed on the member 12. A pair of hinges 22, 22 is provided by means of which the upper member 12 is secured to the back member 19, these hinges being secured to the upper marginal edge of the member 12 by a plurality of rivets 23 and to the wall member 19 intermediate the ends thereof at approximately $\frac{1}{3}$ of its height, by means of other rivets 24, 24 with a filler block 25 being interposed underneath the upper ends of the hinges 22, 22 and the back wall 19. It will be noted that the member 19 abuts against the ends of the rivets 23, thereby tilting the upper member forward slightly, so that when the engine is standing, or when moving at a slow rate of speed, the upper member drops by gravity into the position shown in dotted lines in Figure 3.

In operation the device is exceedingly simple in that it is applied to the smoke box immediately in front of the base of the smoke stack, with the wings 14 and 15 projecting forwardly therefrom, and the upper hinged member in normal position shown in dotted lines in Figure 3. The wings 20 and 21 overlap the wings on the lower member so that when the upper member drops down in the position shown in dotted lines in Figure 3, the back wall 19 of the upper member rests upon the upper edges of the wings 14 and 15 and the device remains in normal stationary position until the rate of speed of the locomotive reaches approximately twenty miles per hour, when the wind, catching in the wings, lifts the upper member upward into position shown in Figs. 1 and 3 in full lines, thus forming a deflector which stands up in front of the locomotive stack forcing the air upward and creat-

ing a current of air upward over the stack which assists in drawing the smoke from the stack by forming a suction over the stack, thus drawing the smoke out of the smoke box and away from the fire and decreasing the resistance on the exhaust nozzles from which the steam is ejected from the cylinders.

As the rate of speed of the locomotive increases the suction also increases, resulting in the carrying of the smoke upward to a considerable height and out of the faces of the enginemen and also to such a height that the smoke does not enter the railway cars. As long as the speed of the train is continued to twenty miles an hour the upper member remains in a vertical position and when the speed decreases below twenty miles an hour, the air current is not sufficient to lift the upper hinged member into vertical position and it falls into a horizontal position as shown in Figure 3, thereby allowing the locomotive to enter depots having smoke jacks and the like, which ordinarily are fairly close to the upper end of the stack and allows sufficient clearance for the locomotive to pass thereunder without tearing away the smoke deflector. These stations where smoke jacks are employed are nearly always closed at one end. Therefore, there is little likelihood of a locomotive encountering a head wind when entering the station, so that the deflector is not lifted, thereby running no danger of catching the deflector against the smoke jacks. And contrary, if a wind of high velocity is traveling in the same direction as the train is moving, the device will remain in horizontal position for a longer time than if the train were moving in the opposite direction to the direction of travel of the wind, but in this case the smoke will be blown upward and carried with the train so as to not interfere with the view of the engine crew or obstruct their view of signals and the like, which is a common happening in the present type of extremely long boilers used in railway service.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. A smoke deflector comprising in combination, a stationary plate and means for securing the plate to a locomotive in front of the smoke stack, the said member having wings formed at each side thereof whereby a channel is formed at the front of the smoke deflector.

2. A smoke deflector comprising in combination, a stationary member of approximately the same height as a locomotive stack, means for securing the plate to the smoke box of a locomotive in the front of the smoke stack, and means at the side of the said plate for preventing the air traveling around the sides of the said vertical plate.

3. A smoke deflector comprising in combination, a stationary member, means for securing the member to a smoke box in front of the locomotive, and a member secured in hinged relation to said first mentioned member.

4. A smoke deflector comprising in combination, a stationary member, means for securing the member to a smoke box in front of the locomotive, and a member secured in hinged relation to said first mentioned member, the said hinged member extending above the stack.

5. A smoke reflector comprising in combination, a stationary member, means for securing the member to the smoke box of the locomotive, a member secured in hinged relation to said first mentioned member, and a hinged member comprising a vertical portion and a wing portion at each of the sides of the said hinged portion.

6. A smoke deflector comprising in combination, a stationary member having wings at the sides thereof, means for securing the member to a locomotive, a member secured in hinged relation to said first mentioned member, the said hinged member comprising a vertical portion and a wing portion at each of the sides thereof, the said hinged member being normally held in inclined position.

7. A smoke deflector comprising in combination, a plate, means for mounting the plate in front of a locomotive smoke stack and a second member hinged to said plate adapted to extend above the stack when in vertical position.

8. A smoke deflector comprising in combination, a plate, means whereby the said plate is secured to a locomotive in front of the smoke stack, and a second member pivotally secured to said plate intermediate its ends, adapted to extend above the said stack when in vertical position.

9. A smoke deflector comprising in combination, a member mounted in front of a locomotive smoke stack, and a member pivotally secured thereto and adapted to be raised into vertical position by air resistance created by the forward movement of the locomotive.

Signed at Blue Island, Illinois, this 26th day of February, 1927.

WILLIAM C. CRIST.
